UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

LINE-CASTING MACHINE.

973,433.

Specification of Letters Patent. Patented Nov. 15, 1910.

Application filed March 22, 1910. Serial No. 550,979.

To all whom it may concern:

Be it known that I, DAVID S. KENNEDY, of borough of Brooklyn, county of Kings, and State of New York, have invented a new and 5 useful Improvement in Line-Casting Machines, of which the following is a specification.

This invention relates to line casting machines of the character shown in Letters 10 Patent of the United States 848,771 and kindred machines, wherein circulating matrices are delivered from two or more distributors to a corresponding number of magazines.

15 The object of the invention is to adapt such machines for speedy adjustment to carry either matrices of ordinary thicknesses or matrices of abnormal thickness, for very large characters, as demanded.

20 To this end, it consists in the employment, between the distributors and the respective magazines, of channeled throats to guide the matrices, of such construction that they may be instantly and individually re- 25 moved and replaced by others having channels of different widths.

Referring to the drawings: Figure 1 is 30 a side elevation of the top of a machine with the upper ends of the magazines, the entrances or throats, and the distributors in vertical section. Fig. 2 is a perspective view showing the series of throats swung outward from their operative position, with one section or throat partially removed.

35 In the drawings, A represents the top portion of a main frame; B, B', B² and B³ the series of stationary inclined longitudinally channeled magazines, arranged one above another and designed to receive and 40 carry the matrices C, these magazines being individually removable at will, that they may be replaced by others containing matrices of different fonts.

45 D, D', D² and D³ represent a series of stationary horizontal bars designed to separate or distribute the matrices for the respective magazines.

50 E, E', E² and E³ are longitudinally channeled throats or entrances, located between the respective distributors and the corresponding magazines for the purpose of receiving the matrices as they fall from the distributor bars, sustaining them on edge, and guiding them downward into the magazine channels.

The throats or entrances E, E', etc., are sustained in an external frame F, provided at its opposite ends with rigid arms f, mounted to turn on pivots f' in the main frame, so that the frame F and the series 60 of throats therein may be swung downward from the operative position shown in Fig. 1, away from the magazines, to the position shown in Fig. 2, for the double purpose of giving access to the upper ends of the magazines and to the interior of the throats.

65 So far as described, the parts are of a known construction, and are not claimed as my invention.

In each of these machines it is frequently 70 desirable to substitute for one or more of the magazines another magazine containing a greater or smaller number of channels, in order that it may carry matrices of larger or smaller size. Each magazine will carry 75 matrices varying in size within certain limits, but a change is necessary when the change in size is very great, for instance from 12 point to 24 point. When this change occurs it is desirable to provide for 80 the new magazine a throat or channel entrance with channels of corresponding width. Heretofore no provision has been 85 made for a speedy or practical change in this regard.

My invention consists in constructing and arranging the throats or entrances E, E', etc., so that they may be individually removed at will. To this end I construct each throat in the manner shown in Fig. 1—with 90 parallel top and bottom plates, e, e' and intermediate partition plates e², secured thereto, the spaces between the plates e² serving as channels to receive and guide the matrices. Each entrance thus constructed is arranged to slide edgewise into and out of the supporting frame F in the manner shown in 95 Fig. 2, the frame being grooved at its ends, or otherwise constructed to give proper support to the throat.

I propose to secure the throats in the frame in any suitable manner. A simple construction is that shown in Fig. 2, in which the throat is provided at each end with a projection e³, arranged to enter a 105 corresponding notch e⁴, in the side of the frame F, which latter is provided with vertically sliding latches e⁵ to engage over the outer edges of the projections, and retain them in place.

It will be manifest to the skilled mechanic that the details of the throat, the supporting frame F, and the means for securing the throats in place may be widely modified within the range of mechanical skill, the only essential requirement being that the throat shall be removable at will from any suitable support.

Having described my invention, what I claim is:

1. In a line casting machine, a plurality of magazines, distributor, and intermediate matrix-guiding throats, in combination with a movable support wherein the throats are mounted, and from which they are independently removable at will.
2. In a machine of the class described, the series of magazines and the corresponding series of distributor in combination with an intermediate swinging frame, and a series of matrix guiding throats mounted in and independently removable from said frame.
3. In a line-casting machine, a magazine,

a distributor, and an intermediate matrix-guiding throat, in combination with a movable support wherein such throat is mounted, and from which it is independently removable at will.

4. In combination with the series of magazines and distributor, an intermediate movable frame provided with a series of matrix guiding throats mounted to slide inward and outward, substantially as described.

5. In a machine of the class described, the series of magazines and distributor in combination with an intermediate swinging frame, a series of throats arranged to slide into and out of said frame, and means for securing the throats in place.

In testimony whereof I hereunto set my hand this seventeenth day of March, 1910, in the presence of two attesting witnesses.

DAVID S. KENNEDY.
